PAUL F. SHIVERS, OF WABASH, INDIANA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

FLUID-FUEL-BURNER CONTROL

Application filed May 7, 1927. Serial No. 189,481.

The object of my invention is to provide a simple and efficient means for automatically controlling the action of a fluid-fuel burner so that it may be depended upon to permit 5 automatic normal operations of the burner but will prevent delivery of fuel in all cases of accidental failure of ignition or combustion, the construction being such that high voltage currents will be available for the fuel 10 motor and ignition means and low voltage currents will be available for the room thermostat, warp switches and circuit breakers sensitive to combustion conditions.

The accompanying drawing illustrates my 15 invention diagrammatically, high voltage circuits being shown in heavy lines and low voltage circuits being shown in light lines.

In the drawings 10 and 11 indicate the power leads, 12 the primary of transformer 20 T and 13 and 14 connections between said primary and the power leads 10 and 11.

The burner motor M is electrically connected by wire 15 to one terminal 16 of a motor-actuated circuit breaker S and to one 25 terminal 17 of an ignition circuit breaker IS. Said motor M is also connected by wire 18 with lead 10.

Paired with terminal 16 is a terminal 20 in one end of a mercury tube 21 carried by 30 the pivotally supported body 22 of switch S, said body being reciprocated by a plunger 23 which controls a fuel valve 24 in the fuel supply line, said plunger 23 being actuated in one direction by a reducing train 25 from the 35 rotor 26 of the supplemental valve motor VM. Plunger 23 is biased against the action of the rotor by a spring 27. Terminal 20 is connected by wire 19 with lead 11.

Paired with terminal 17 is a terminal 30 in 40 one end of a mercury tube 31 carried by a pivoted carrier 32 of the ignition switch IS. Said carrier 32 is biased to circuit-breaking position, against the yielding resistance of a dash-pot D, by weight or spring and is moved 45 to circuit-making position by a pin 33 carried by plunger 23, said pin acting upon the carrier 32 in one direction only.

Terminal 30 is connected by a wire 35 with 50 electrical ignition mechanism I which, in the drawing, is indicated as comprising spark

means 36 and electrical pilot gas valve 37 which are connected by wire 38 with lead 10.

The secondary 40 of transformer T is connected by wire 41 with one end of the stator 42 of the valve motor VM, the opposite end of said stator being connected by wire 43 with the leaf 44 of a warp switch W, said leaf being normally held in electrical contact with terminal 45 against the bias of spring 46. Electrically insulated from leaf 44 of the warp switch W is a bi-metallic blade 47 which normally holds leaf 44 in contact with terminal 45. Electrically connected to blade 47 is one end of a heating coil 48, the opposite end of which is connected by wire 49 with terminal 45. A wire 50 connects heating coil 48 and terminal 45 with a terminal 51 in the hot end of a mercury tube 52 which is part of a combustion control element C which is sensitive to combustion conditions adjacent 55 the burner.

Paired with terminal 51 is a terminal 53 which is electrically connected with a terminal 54 in the cold end of tube 52 and terminals 53 and 54 are connected by wire 55 with blade 47.

Paired with terminal 54 in the cold end of tube 52 is a terminal 60 which is connected by wire 61 with a terminal 62 adapted to be contacted by a movable terminal 63 which is under the influence of plunger 23. Terminal 63 is connected by a wire 64 with wire 55 and therefore with blade 47 and terminals 53 and 54. The room thermostat R has one side connected by a wire 70 with wire 41 and through that wire to secondary 40 and stator 42. The other side of the room thermostat R is connected by wire 71 with the heating coil 72 of a warp switch w, said coil being connected to the bi-metallic blade 73 of said warp switch which blade is connected by wire 74 with secondary 40 of transformer T. The blade 73 is cold-separated from terminal 75 of the warp switch w and said terminal is connected by wire 76 with wire 61 and therefore with terminals 60 and 62.

The operation is as follows:

The diagram shows the parts in cold position.

Upon demand for heat at R the circuit 40— 100

74—73—72—71—R—70—41—40 if closed with sufficient definiteness at the room thermostat R, will cause a warping of blade 73 to close contact of said blade with terminal 75, thus establishing the circuit 40—74—73—75—76—61—60—54—55—47—48—49—45—44—43—42—41—40, thus energizing the supplemental motor VM to shift plunger 25 to open fuel valve 24, shift circuit breaker S to circuit-closing position, and release ignition switch IS.

Connection of terminals 16—20 completes the fuel motor circuit 11—19—20—16—15—M—18—10. Connection of terminals 16—20 also completes the ignition circuit 11—19—20—16—15—17—30—35—36—37—38—10 and in due course, dependent upon the adjustment of the dash-pot D, circuit breaker IS opens the ignition circuit at 17—30.

20 The opening movement of plunger 23 also moves terminal 63 into contact with terminal 62 and thereby shorts out the cold side of the combustion control C providing for motor VM the circuit 40—41—42—43—44—45—25 49—48—47—55—64—63—62—61—76—75—73—74—40, the shunt circuit 70—R—72 being maintained to keep coil 72 heated and thus maintain the contact 73—75.

30 If ignition of the fuel takes place within the time interval before the ignition circuit breaker IS moves to circuit breaking position, the combustion control C will move to hot position, thus breaking the circuit at 60—54 and making a circuit at 51—53, thus providing 35 40—41—42—43—44—45—49—50—51—53—55—64—63—62—61—76—75—73—74—40 which maintains current in the stator of the supplemental motor VM and shunts out the heating coil 48 of the warp switch W.

40 The apparatus remains in this condition so long as proper combustion is maintained at the burner and the room thermostat R calls for heat.

Upon break at the room thermostat R the 45 supplemental motor VM is deenergized and spring 27 returns valve 24, circuit breakers S and IS and terminal 63 to initial position, whereupon fuel delivery is discontinued.

If combustion fails for any reason the combustion control returns to the cold position, thus returning the heating coil 48 into the supplemental motor circuit, whereupon, in the course of predetermined time the warp switch W is actuated and the circuit of the 55 supplemental motor is broken at 44—45 and manual reset is necessary to put the apparatus in commission.

The warp switch W is not an absolute essential in this construction because the room thermostat R may be substituted for it, but the provision of the warp switch W eliminates some objections which flow from a fluttering of the room thermostat.

While I have illustrated mercury tube 65 switches at various points it will be readily

understood that any desired form of circuit breaker suitable for handling the necessary current may be substituted without departing from my invention. It will also be understood that the details of motor VM and its connection with the switches actuated thereby may be considerably modified and that it is not absolutely essential that this motor actuates a fuel valve because, while such a valve is quite desirable to insure against leakage of fuel past the fuel delivering apparatus driven or controlled by motor M, such apparatus controlled by motor M may be solely relied upon to control the flow of fuel.

For convenience motor M may be called the fuel motor and motor VM may be called the supplemental motor. The details of the warp switch may be varied, the essential characteristic being that there be a retarded circuit-breaking action after a predetermined time interval of current flow in the absence of combustion at the burner, and the term "warp switch" in the claims is used to designate such a device generally, and the term heating coil is used to designate generally the element thereof electrically causing delayed circuit-breaking action.

The fuel motor may drive or control a fuel pump or other fuel-flow control means and may drive movable parts of the burner proper.

The term "room thermostat" is used to designate a main circuit-controlling element sensitive to thermal or other conditions to be affected by the burner.

These various details may be varied through a wide range without departing from my invention.

The details of construction of the fuel valve forms the subject matter of my co-pending application Serial No. 111,154.

I claim:

1. In a control system for fluid-fuel burners, a burner motor; a supplemental motor; a circuit-breaker actuated by said supplemental motor and comprising a pair of terminals; a circuit-breaker sensitive to combustion conditions adjacent the burner and comprising a cold-pair of terminals and a hot-pair of terminals; a warp switch comprising a heating coil; a transformer; electrical connections from power to one terminal of the motor-actuated circuit-breaker and from power to fuel motor; electrical connections from power to the motor-actuated circuit breaker; electrical connections from the motor-actuated circuit-breaker to the fuel motor; electrical connections from the transformer secondary to the supplemental motor, the warp switch and its heating coil, and to one terminal of both the hot and cold pairs of terminals of the circuit-breaker sensitive to combustion conditions adjacent the burner; electrical connections between the warp switch, its heating coil, and the other terminal of the hot-pair of the circuit-breaker.

sensitive to combustion conditions adjacent the burner whereby said circuit-breaker in the hot position will shunt out said heating coil; electrical connections between the warp 5 switch, warp switch heating coil and transformer secondary, comprising two separable terminals one of which is moved to and from its fellow by said supplemental motor; and a room thermostat connected to the transformer secondary to control flow of current through said secondary.

2. In a control system for fluid-fuel burners, a burner motor; a supplemental motor; a circuit-breaker actuated by said supplemental 15 motor and comprising a pair of terminals; electrical ignition mechanism; a delayed-action circuit-breaker biased to open position; one-way actuating mechanism controlled by the supplemental motor for moving the ignition 20 circuit-breaker to normal closed position; a circuit-breaker sensitive to combustion conditions adjacent the burner and comprising a cold-pair of terminals and a hot-pair of terminals; a warp switch comprising a heating 25 coil; a transformer; electrical connections from power to one terminal of the motor-actuated circuit-breaker, from power to fuel motor, and from power to ignition means; electrical connections from ignition means to 30 the delay-action circuit breaker; electrical connections from ignition circuit breaker to the motor-actuated circuit breaker; electrical connections from the motor-actuated circuit-breaker to the fuel motor; electrical connections 35 from the transformer secondary to the supplemental motor, the warp switch and its heating coil, and to one terminal of both the hot and cold pairs of terminals of the circuit-breaker sensitive to combustion conditions 40 adjacent the burner; electrical connections between the warp switch, its heating coil, and the other terminal of the hot-pair of the circuit-breaker sensitive to combustion conditions adjacent the burner whereby said circuit-breaker in the hot position will shunt out said heating coil; electrical connections 45 between the warp switch, warp switch heating coil and transformer secondary, comprising two separable terminals one of which is moved to and from its fellow by said supplemental motor; and a room thermostat connected to the transformer secondary to control flow of current through said secondary.

3. In a control system for fluid fuel burners, a burner motor; a supplemental motor; a reciprocable member controlled by the supplemental motor; means biasing said reciprocable member in opposition to the supplemental motor; a circuit-breaker actuated by 55 said reciprocable member and comprising a pair of terminals; a circuit-breaker sensitive to combustion conditions adjacent the burner and comprising a cold-pair of terminals and a hot-pair of terminals; a warp switch comprising a heating coil; a transformer; elec-

trical connections from power to one terminal of the motor-actuated circuit-breaker, from power to fuel motor; electrical connections from power to the motor-actuated circuit breaker; electrical connections from the motor-actuated circuit-breaker to the fuel motor; electrical connections from the transformer secondary to the supplemental motor, the warp switch and its heating coil, and to one terminal of both the hot and cold pairs 70 of terminals of the circuit-breaker sensitive to combustion conditions adjacent the burner; electrical connections between the warp switch, warp switch heating coil and transformer secondary, comprising terminals controlled by said reciprocable member; and a room thermostat connected to the transformer secondary to control flow of current through 75 said secondary.

4. In a control system for fluid-fuel burners, a burner motor; a supplemental motor; a reciprocable member actuated by said supplemental motor in one direction; means biasing said reciprocable member in opposition to the supplemental motor; a circuit-breaker actuated by said reciprocable member and comprising a pair of terminals; electrical ignition mechanism; a delayed-action circuit-breaker biased to open position; one-way actuating mechanism controlled by the reciprocable member for moving the ignition circuit-breaker to normal closed position; a circuit-breaker sensitive to combustion conditions adjacent the burner and comprising a cold-pair of terminals and a hot-pair of terminals; a warp switch comprising a heating coil; a transformer; electrical connections from power to one terminal of the motor-actuated circuit breaker, from power to fuel 100 motor, and from power to ignition means; electrical connections from ignition means to the delay-action circuit breaker; electrical connections from ignition circuit breaker to the motor-actuated circuit breaker; electrical connections from the motor-actuated circuit-breaker to the fuel motor; electrical connections from the transformer secondary to the supplemental motor, the warp switch and its heating coil, and to one terminal of both 105 the hot and cold pairs of terminals of the circuit-breaker sensitive to combustion conditions adjacent the burner; electrical connections between the warp switch, its heating coil, and the other terminal of the hot-pair of the circuit-breaker sensitive to combustion conditions adjacent the burner whereby said circuit-breaker in the hot position will shunt out said heating coil; electrical connections 110 between the warp switch, warp switch heating coil and transformer heating coil; electrical connections from power to one terminal of the motor-actuated circuit-breaker, from power to fuel motor, and from power to ignition means; electrical connections from ignition means to the delay-action circuit breaker; electrical connections from ignition circuit breaker to the motor-actuated circuit breaker; electrical connections from the motor-actuated circuit-breaker to the fuel motor; electrical connections from the transformer secondary to the supplemental motor, the warp switch and its heating coil, and to one terminal of both 115 the hot and cold pairs of terminals of the circuit-breaker sensitive to combustion conditions adjacent the burner; electrical connections between the warp switch, its heating coil, and the other terminal of the hot-pair of the circuit-breaker sensitive to combustion conditions adjacent the burner whereby said circuit-breaker in the hot position will shunt out said heating coil; electrical connections 120 between the warp switch, warp switch heating coil and transformer heating coil; electrical connections from power to one terminal of the motor-actuated circuit-breaker, from power to fuel motor, and from power to ignition means; electrical connections from ignition means to the delay-action circuit breaker; electrical connections from ignition circuit breaker to the motor-actuated circuit breaker; electrical connections from the motor-actuated circuit-breaker to the fuel motor; electrical connections from the transformer secondary to the supplemental motor, the warp switch and its heating coil, and to one terminal of both 125 the hot and cold pairs of terminals of the circuit-breaker sensitive to combustion conditions adjacent the burner; electrical connections between the warp switch, its heating coil, and the other terminal of the hot-pair of the circuit-breaker sensitive to combustion conditions adjacent the burner whereby said circuit-breaker in the hot position will shunt out said heating coil; electrical connections 130 between the warp switch, warp switch heating coil and transformer heating coil.

- coil and transformer secondary, comprising terminals controlled by said reciprocal member; and a room thermostat connected to the transformer secondary to control flow of current through said secondary.
5. A control system having the characteristics specified in claim 1, wherein the room thermostat is in circuit with a warp switch arranged to control flow of current to the supplemental motor.
10. 6. A control system having the characteristics specified in claim 1 and wherein a fuel valve, controlled by the supplemental motor, controls flow of fuel relative to the burner.
15. 7. A control system having the characteristics specified in claim 2 wherein the room thermostat is in circuit with a warp switch arranged to control flow of current to the supplemental motor.
20. 8. A control system having the characteristics specified in claim 3 wherein the room thermostat is in circuit with a warp switch arranged to control flow of current to the supplemental motor.
25. 9. A control system having the characteristics specified in claim 4 wherein the room thermostat is in circuit with a warp switch arranged to control flow of current to the supplemental motor.
30. 10. A control system having the characteristics specified in claim 2 and wherein a fuel valve, controlled by the supplemental motor, controls flow of fuel relative to the burner.
35. 11. A control system having the characteristics specified in claim 3 and wherein a fuel valve, controlled by the supplemental motor, controls flow of fuel relative to the burner.
40. 12. A control system having the characteristics specified in claim 4 and wherein a fuel valve, controlled by the supplemental motor, controls flow of fuel relative to the burner.
